UNITED STATES PATENT OFFICE.

FRANK. SCHREIDT, OF MANSFIELD, OHIO, ASSIGNOR TO THE SCHREIDT & MILLER COMPANY, OF SAME PLACE.

MACHINE FOR ROLLING CARRIAGE-TOP IRONS.

SPECIFICATION forming part of Letters Patent No. 372,711, dated November 8, 1887.

Application filed January 12, 1886. Serial No. 188,359. (No model.)

To all whom it may concern:

Be it known that I, FRANK. SCHREIDT, of Mansfield, county of Richland, and State of Ohio, have invented a new and useful Improvement 5 in Machines for Rolling Carriage-Top Irons, of which the following is a full, clear, and exact description, reference being had to the accompanying drawings, making part of this specification.

10 My invention relates to a novel construction of the rolls or roller-dies for giving to the iron bars used for carriage-top bows, and other irons, the desired form and the desired uniformity in size, and to the means employed, in connection 15 with said rolls, for controlling or guiding and stopping the irons to be operated upon, as hereinafter described and claimed.

In the accompanying drawings, Figure 1 represents a side or front elevation of so much of 20 a rolling-machine as is necessary to show my improvements; Fig. 2, a plan view of the same; and Fig. 3, a vertical transverse section taken on the line *x x*, Fig. 1.

A, A', A², and A³ indicate stout uprights 25 secured, in practice, to any suitable frame or base, and provided in their upper ends with bearings for a shaft or shafts, B B', having a band or driving wheel or wheels, C and C', secured to them, through which motion is imparted to said shaft or shafts in any suitable manner.

The machine will be described as though the shaft B B' were divided and each part driven independently of the other; but it will be apparent that it might be made continuous, in 35 which case only a single driving or band wheel would be required. On the shaft B' is secured a roll, D, having one or more grooves, *d*, in its periphery, and upon a short shaft, B², mounted 40 and adjustable in suitable bearing-blocks in the standards A² and A³, is a second roll, D', having a similar groove or grooves, *d'*, in its periphery, the counterpart of that in roll D, and forming in connection therewith the die 45 in which the bar to be operated upon is rolled and reduced to the desired size. The shaft B' has upon it, adjacent to the roll D, a spur-gear, E, in mesh with a similar gear, E', on shaft B², for imparting to the latter a rotary 50 movement in the reverse direction to that of shaft B' and its roll, causing the contiguous

portions of the two rolls acting on the metal to move together.

The periphery of the roll D at the sides of and adjacent to the groove *d* is beveled at *d*² 55 to give to the edges of the groove a sharpened or cutting form or edge, and the roll D' may be similarly formed; but I prefer to reduce the diameter of the latter abruptly through a vertical shoulder, or one perpendicular to the 60 shaft of said roll at the sides of the groove *d'*, thereby giving sharp cutting-edges to the roll D' at the sides of the groove, which serve, in connection with the edges of roll D, to remove from the iron operated upon any surplus metal 65 which cannot be compressed into the die or grooves.

To the standards A² and A³, in front of the groove formed between the contiguous faces of the rolls D and D', is secured a stout guide 70 and stop bar, F, provided directly in front of said groove with a slot or perforation, *f*, conforming in shape, preferably, to that of the grooves or die in the rolls, and of sufficient size to permit the bar of iron to be fed through 75 it, and guided thereby to said rolls. Said bar F serves also to prevent the passage of the knuckle or joint on the end of the iron operated upon, and so serves as a stop for regulating the portion to be left adjacent to such 80 knuckle in the squared or unrolled form of the bar.

Upon the shaft B and a short shaft mounted 85 in bearings in standards A and A' are arranged rolls G and G', geared together and operating in a manner similar to rolls D and D', and provided with grooves *g g'* and *g² g³* in their peripheries, as shown. The grooves in rolls G and G' are not provided with cutting-edges, 90 for the reason that the surplus metal is supposed to have been removed by the passage of the bars between the rolls D and D' for that purpose; but the grooves *g g'* are by preference formed edgewise in the faces of the rolls, and serve to remove and roll into the body of 95 the iron any fin or fins formed or left upon it by the action of the cutting-rolls D and D', while the grooves *g²* and *g³* are formed flatwise in the rolls and of the exact form and size which it is desired that the rolled portion of 100 the iron shall assume when completed. A perforated guide and stop bar, F', similar to

that at F, is secured to the forward faces of the standards A and A', and for a similar purpose.

H represents a tube secured to a frame-bar, 5 A⁴, in rear of the rolls, with one end in close proximity thereto, as shown, into which the iron bar passes after being acted upon by the rolls, said tube serving to receive and hold the iron and prevent its adhering to and following 10 one of the rolls and being curled up thereby, in a manner that will be readily understood.

Provision is made for the support of a similar tube in rear of rolls D and D'.

I is a pipe with branches for supplying water to the rolls for keeping them cool.

Aside from the features of construction and arrangement of parts hereinabove specifically described, the machine in its organization and construction may be similar to that described 20 in another application filed by me of even date herewith.

Having now described my invention, I claim as new—

1. In a machine for rolling carriage-top and 25 similar irons, the rolls between and in grooves in which the iron is rolled into the desired shape, provided with cutting-edges adjacent to the grooves in their peripheries for removing surplus metal from the bars operated upon 30 in the process of rolling the same, substantially as described.

2. The combination, with the rolls having the peripheral grooves and cutting-edges, of the perforated guide-bar through which the iron is fed to the rolls, substantially as described. 35

3. The combination, with the rolls having the forming-grooves and cutting edge or edges, of the finishing-rolls for operating on the irons after they have been subjected to the reducing 40 or cutting rolls, substantially as described.

4. The combination, with the grooved cutting and reducing rolls, of the perforated guide-bar through which the irons are fed to the rolls, and the receiving-tubes for receiving the irons from the rolls and straightening or preventing the curling of the same, said 45 guide and receiving tubes being arranged to adapt the irons to be passed transversely between the rolls, substantially as described. 50

5. The combination of the cutting and reducing rolls, the finishing-rolls, and the perforated guide and receiving tubes, arranged and operating substantially as described.

In testimony whereof I have hereunto set 55 my hand this 7th day of January, A. D. 1886.

FRANK. SCHREIDT.
